UNITED STATES PATENT OFFICE

MANUEL F. ROSE, OF ALAMEDA, CALIFORNIA

PERPETUAL CALENDAR

Application filed November 14, 1928. Serial No. 319,229.

The invention relates to a device providing a calendar of the perpetual type.

An object of the invention is to provide a perpetual calendar in which the displayed data for a particular month is usable in its entirety and without any element of uncertainty.

Another object of the invention is to provide in a calendar of the class described a particularly effective means for displaying a table of the days of a week in their proper relation for a particular month.

A further object of the invention is to provide the aforesaid calendar with means positively indicating the number of days in a particular month independently of said table therefor.

Yet another object of the invention is to provide a device of the character described having a particularly simple structure for accomplishing the purposes thereof.

The invention possesses other objects and features of advantage, some of which, with the foregoing, will be set forth in the following description of a preferred form of the invention which is illustrated in the accompanying drawings, in which:

Figure 1 is a face view of a calendar embodying the invention.

Figure 2 is a back view of the calendar, portions of different members thereof being progressively broken away.

Figure 3 is an enlarged sectional view taken on the line 3—3 in Figure 1.

Figure 4 is a minified face view of a scroll and rollers therefor forming part of the device.

Figure 5 is a face view of an indicator disc member of the structure.

As herewith particularly disclosed, the device of my invention is mounted in and on a casing 6 in the form of a continuous rectangular frame having an inwardly directed flange portion 7 defining a reduced sight opening for the frame. A transparent and imperforate pane 8 is disposed in the frame opening with its edges against the inner side of the frame flange, said pane being preferably, though not necessarily, of glass.

Mounted behind the pane 8 is a mat member

9 providing generally centrally therein an opening 11. A plate 13 is disposed behind the mat member 9, said plate being imperforate behind the mat opening and fitting the frame opening whereby its definite position within the frame is assured.

Mounted on the back of the frame and adjacent opposite ends thereof are rollers 14 and 15, said rollers being parallelly related and being journalled in bearing members 16 mounted on the frame adjacent opposite edges thereof. The rollers are preferably cylindrical and of constant section therealong except at the bearings where they are reduced slightly for engagement in the bearing bores of complementary size and so are arranged to be held against accidental axial displacement from their mounting in said bearings in a particularly simple manner. A scroll 17, bearing indicia to be hereinafter more specifically described, is mounted on the rollers with the extremities thereof secured to the different rollers in a suitable manner. The scroll portion which lies between the rollers is disposed between the mat 9 and the plate 13 whereby a predetermined length thereof is arranged for display in the mat opening 11, the scroll being rolled from one roller to the other to display predetermined portions thereof as required.

For permitting the aforesaid disposition of the scroll, the plate 13 is notched from its opposite ends in the manner shown at 18 in Figure 2, whereby the remaining end portions 21 of said plate lying generally at opposite sides of the scroll rolls remain for engaging the frame to fix the plate therein against lateral displacement. Preferably, and as particularly disclosed in Figure 2, the rollers 14 and 15 are arranged to overlie and cooperate with the plate 13 at the portions 21 thereof whereby this plate and the other members in front of it in the frame may be secured in their proper relative positions, and may be freely removed by and upon a removal of one or both of the rollers. As shown, a paper backing member 23 is disposed on the back faces of the frame and plate 13, and beneath the rollers, said member 23 being, of course, suitably perforated

opposite the plate notches 18 and serving to seal the assembled device to a maximum degree. Knobs 24 are provided on the rollers for turning the same, it being noted that a slight frictional engagement of the rollers with the member 23 is preferably provided for preventing a turning of a roller except when the scroll is deliberately drawn from one roller to another for effecting a change of the displayed scroll portion.

Means are provided for displaying in fixed position adjacent the mat opening, indicia indicating the days of the week. As particularly disclosed, the appropriate symbols 26 are printed on the mat 9 laterally of the exposed scroll portion, the scroll edges thus being arranged for concealment and retention beneath the mat at all times. The various symbols 26 are arranged in a line extending along and just above the upper edge of the mat opening 11 and are equally spaced in their line, the seven days of the week being indicated by appropriate abbreviations therefor.

Referring now to the scroll 17, it is seen by reference to Figure 4 that said scroll has provided therealong four distinct sets or tables of numbers separated by spaces 27, said tables being indicated in order by the numbers 29, 28, 30 and 31. Each of said tables provides thirteen columns of figures spaced longitudinally of the scroll with the same spacing as that of the symbols of the indicia 26 on the mat 11. The numbers of each table are also arranged in rows directed longitudinally of the scroll. Considering generally the aforesaid number tables, it is seen that the numbers thereof begin with one, that the numeral one is in the top row, that the successive numbers in the rows are progressively larger by one in order toward the right-hand sides of the tables, and that the numbers in each column are progressively seven units larger when considered in a downward direction in the column. By this arrangement it is seen that if any group of seven columns be considered by itself, a succession of numbers is displayed without duplication and in the usual order or arrangement of calendar numbers.

Referring specifically to the table 31, it is seen that the largest number displayed is thirty-one and that such number will be displayed no matter where the group of columns is chosen. Assuming this table disposed behind the mat 9, if the first day of a month should occur on a Sunday, the column headed by the numeral one would be disposed under the symbol "Sun" on the mat and the remaining day numbers for the month would occur under the appropriate day symbols. In this manner, the table may be disposed to display a proper arrangement of day numbers in conformity with the day of the week on which a particular numbered day falls and the table

may thus be used perpetually. The particular setting described, it is noted, is that shown in Figure 1, it being noted that the mat opening 11 is of such width as to permit a simultaneous display of but seven number columns thereat.

But some months have but thirty days, while February has twenty-eight or twenty-nine. Since the table 31 presents numbers for a thirty-one day month, uncertainty as to which day is the last day of the month would frequently arise if this table were to be used for all the months and the accuracy of the use of the table would be seriously interferred with. Accordingly, and as shown, the table 28 is specifically numbered as for a twenty-eight day month, the table 29 for a twenty-nine day month, and the table 30 for a thirty day month, and the appropriate exact table is thus provided for use during any particular month. Obviously, the various tables differ only in the highest number displayed and are otherwise alike. In this manner, a perpetual calendar is provided which, when set for a particular month, may thereafter be used without any element of perplexity.

For facilitating a setting of the scroll in the manner hereinbefore indicated, the spaces 27 are provided with suitable indicia 32 directing an operator toward the desired table, the tables 29 and 28 being preferably provided at one end of the scroll in the order shown, since they are used so much less frequently than are the tables 30 and 31.

Means are also preferably provided in the device for designating the month and the number of days therein, and as shown, such means comprises a displaceable member 33 disposed forwardly of the plate member 13 and behind the displayed scroll portion whereby it is generally concealed behind the mat 9 and said scroll portion. Openings 34 and 35 are provided in the mat laterally of said scroll portion for viewing limited portions of the member 33, which portions are provided with suitable indicia. As particularly shown, the opening 34 is provided in the mat above the line of day symbols 26, and the opening 35 is provided in the mat at the opposite side of said scroll portion. In the present embodiment, the member 33 comprises a disc pivotally fixed to the member 13 for rotation about its center and with its pivotal axis lying between, and in the line of, the mat openings 34 and 35. The pivot point of the disc is nearer the opening 34 and the disc is arranged to protrude slightly from the upper frame edge whereby it may be manually turned, the frame being appropriately slotted as at 36 and 37 to permit the use of a disc of sufficient diameter to provide for said protrusion thereof.

Referring to Figure 5, it will be seen that the lines of symbols 38 and 39 are provided on the outer face of the disc 33, said lines being

circular and concentric, with their common center of curvature at the disc center. The symbols 38 of the inner line are those of the twelve months of the year and are arranged to be displayed in the opening 34. The symbols 39 are members which disclose the number of days in the month the symbol 38 of which occurs diametrically opposite a given symbol 39. Since in leap-year, the month 10 of February has twenty-nine days rather than twenty-eight as in other years, the symbol for February is provided twice in the line of month symbols, and the numbers twenty-eight and twenty-nine are provided opposite 15 said symbols and in the number line. Preferably, though not necessarily, the symbols 38 and 39 are arranged as shown wherein, with the exception of one of the symbols for February and its corresponding number, two-month symbols 38 and two-number symbols 39 occur in the same diametral line. This arrangement permits the provision of larger symbols on the disc, and so is generally desirable for at least the smaller sizes of the 25 device.

It will now be clear that the use of the disc 33 in connection with the display of the appropriate table of the scroll, is arranged to disclose the exact calendar data needed for 30 a particular month without any element of uncertainty, thereby accomplishing a major object of the present invention. And, furthermore, the structure described is a particularly simple one for providing for a performance of the desired functions thereof.

From the foregoing description taken in connection with the accompanying drawings, the advantages of the construction and method of operation will be readily understood by 40 those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the 45 appended claims.

Having thus described my invention, I 50 claim as new and desire to secure by Letters Patent of the United States the following:

1. In a device of the class described, a frame, a mat member providing a sight opening, rollers mounted in said frame at opposite 55 sides of said opening, a scroll cooperatively carried by and between said rollers and arranged to have different portions thereof displayed in said opening, said scroll carrying tables of calendar dates on the viewable face 60 thereof and having the symbols thereof arranged in columns for selective display at said opening, said mat member having indicated thereon the days of the week for simultaneous registration with the displayed 65 columns of a table and being provided with

relatively spaced additional sight openings laterally of said first opening thereof, and a disc member rotatably mounted behind said mat member and disposable to simultaneously display in different said last mat 70 openings indicia thereon respectively designating the month and the number of days in said month appropriate to the displayed portion of a table.

2. In a mounting for a scroll bearing indicia and carried on a pair of rollers, a frame having a forward and inwardly directed flange defining a reduced front sight opening for the frame, a transparent pane fittedly engaged in the frame and behind said flange, a mat engaged behind said pane and having a central sight opening, a back plate engaged in the frame behind said mat and arranged for the disposal of a scroll portion between the rollers between itself and said mat, and means for journalling said rollers on said frame and with said portion thereof between the said plate and mat whereby said rollers engage the said plate for securing the pane and mat and plate in the frame.

3. In a device of the class described, a scroll having provided on a face thereof a table of calendar dates having the date numbers so arranged that any group of seven adjacent columns of a table will provide in regular order numbers corresponding to all the days of a month, rollers carrying said scroll on and between them, a frame having a forward and inwardly directed flange therearound defining a reduced front sight opening for the frame, a mat engaged behind said flange and having a central sight opening for the display therein of a said group of seven columns of said numbers, a back plate engaged in the frame behind said mat and having the scroll portion between the rollers engaged between itself and the mat to display a selected said group of numbers in the said sight opening of the mat, and means journalling said rollers on and to said frame whereby said rollers engage said plate for securing the mat and plate in the frame and said rollers are frictionally and displaceably held against rotation.

In testimony whereof I affix my signature.

MANUEL F. ROSE.
